UNITED STATES PATENT OFFICE

2,630,842

THREAD CONTROL FOR WEFT REPLENISHING LOOMS

Richard G. Turner, Worcester, Mass., assignor to
Crompton & Knowles Loom Works, Worcester,
Mass., a corporation of Massachusetts

Application December 11, 1951, Serial No. 260,974

11 Claims. (Cl. 139—257)

1

This invention relates to improvements in thread control means for the thread of a transferred bobbin in an automatic bobbin changing loom and it is the general object of the invention to provide simple means controlled by the bobbin transerrer mechanism for locating the thread and its thread holder in a rearward position favorable for self-threading of a freshly replenished shuttle and then locate the thread forwardly to favor its movement under the filling fork of a filling stop motion.

Bobbin changing looms customarily employ a magazine containing reserve bobbins the weft ends of which are led to some form of thread holder. At the time of a bobbin change the selected bobbin is transferred into the depleted shuttle and the latter is then picked to the opposite side of the loom. The thread of the new bobbin in the shuttle is held by the holder to facilitate self-threading of the shuttle. Many looms employing bobbin changing mechanisms are equipped with a weft stop motion having a filling fork near the center of the lay which must be supported by the weft to permit continued loom operation. The thread holder should be in rear position to favor self-threading of a freshly replenished shuttle, but this position is unfavorable for movement of the thread under the stop motion fork.

Heretofore I have proposed means for locating the thread holder to two different positions incident to a weft replenishing operation in the first of which the thread holder is located rearwardly and in the other of which the thread holder is in forward position. Such mechanism is shown for instance in my prior Patent No. 2,531,177. In that patent however the swinging mounting for the thread holder always has an operation whenever the loom indicates for a bobbin change even though a misplaced shuttle cancels the call for replenishment by well-known revoker mechanism. In such cases the thread holder has an unnecessary and useless motion.

It is an important object of the present invention to provide operating mechanism for the thread holder adaptable for use on looms having stationary reserve bobbin magazines and set into operation by movement of the bobbin transerrer mechanism. With such a control the thread holder will not have the previously mentioned unnecessary useless motion because of the fact that if a misplaced shuttle should cancel a call for bobbin change the transerrer mechanism will not operate and the thread holder will remain at rest. It should be understood, however, that the present invention is not limited

to use on looms equipped with stationary magazines, but is usable on any loom having bobbin transerrer mechanism.

The thread holder control mechanism shown in the previously mentioned patent has in the past been used more particularly on looms wherein the force for moving the thread holder is derived from a two-pick cam located a considerable distance from the thread holder. The present invention relates more particularly to thread holder control mechanism which can be operated by a one-pick cam located much nearer the thread holder due to the fact that the operating cycle, being initiated by the transerrer mechanism, begins relatively late in the replenishing operation and can be completed within one pick of the loom. By using this type of control it is possible to derive the forces which effect movement of the thread holder backwardly and forwardly from the top or crank shaft which is relatively high in the loom. The invention, however, is not limited to use with a one-pick cam.

It is a more particular object of the present invention to secure a cam to the top shaft of the loom which completes a rotation each pick of the loom and associate it with a rockable operator lever connected to the thread holder and normally non-aligned with the cam but is swung into alignment with the cam by the bobbin transerrer mechanism so that the operator lever can be rocked for the purpose of giving the thread holder its back and forth movements.

In order that the invention may be clearly understood reference is made to the accompanying drawings which illustrate by way of example the embodiments of the invention and in which:

Fig. 1 is a side elevation of a loom showing a multistack stationary reserve bobbin magazine and having a movable thread holder controlled by mechanism forming the subject matter of the present invention.

Fig. 2 is an enlarged plan view looking in the direction of arrow 2, Fig. 1, partly in section.

Fig. 3 is an enlarged detailed section on line 3—3, Fig. 2, showing part of the mechanism in two different positions.

Figs. 4 and 5 are enlarged vertical sections on lines 4—4 and 5—5, respectively, Fig. 2.

Fig. 6 is an enlarged plan view partly in section looking in the direction of arrow 6, Fig. 1, showing part of the controller between the transerrer mechanism and the operator lever for the thread holder.

Fig. 7 is an enlarged plan view partly in sec-

2

tion looking in the direction of arrow 1, Fig. 1, showing the pivotal mounting for the thread holder.

Fig. 8 is a diagrammatic view showing the parts in normal position.

Fig. 9 is a view similar to Fig. 8 but showing the parts in the position which they occupy after the swinging operation of the thread holder has been initiated.

Fig. 10 is a diagrammatic view showing the manner in which the actuator cam and operator lever effect movement of the thread holder.

Fig. 11 is a diagrammatic plan view indicating the lay in full lines in the position which it occupies at the time of picking of the replenished shuttle and in dotted lines in the position which it occupies after the shuttle has passed the fork of the center filling stop motion, and

Fig. 12 is a side elevation of the cam used as an actuator for moving the operator lever.

Referring to Fig. 1, the loom frame 1 supports a stationary reserve bobbin magazine M which in the present instance is provided with four stacks of vertically arranged reserve bobbins indicated generally at 2. The reserve bobbins have extending from them threads or weft ends 3 leading to a thread holder H shown here as being of the geared type employing gears 4 and 5 which turn in opposite directions to draw the weft ends away from the magazine. The thread holder H is fastened to a lever 6 the upper end of which has a hub 7, see Fig. 7, which in the present instance is rockable on one of the tie rods 8 forming part of the magazine M. Collars 9 on the tie rod limit the position of the hub 7 along the tie rod.

The loom is provided with a lay 10 having a shuttle box 11 for receiving any one of several self-threading shuttles one of which is shown at S. The usual picking mechanism (not shown) may be employed for picking the shuttle out of the shuttle box 11, the picking operation ordinarily occurring when the lay is moving backwardly and is near or at its top center position. The lay is reciprocated by connectors one of which is shown at 15 operated by the top or crank shaft 16 which has a rotation once for each pick or beat of the loom, and during a rotation thereof causes the lay to pass from front center through top, back and bottom centers and return to front center to complete a one-pick cycle.

The lay is provided with a bunter 17 for operation of a bobbin transerrer mechanism designated generally at A. This mechanism includes a latch 18 pivoted to a transerrer arm 19 which is normally in raised position as shown in Fig. 1. At the time of a bobbin changing operation the latch 18 is raised by well-known mechanism (not shown) into the path of the bunter 17, and as the lay moves forwardly, to the left as viewed in Fig. 1, and approaches front center after having passed bottom center, the bunter engages the latch and rocks the transerrer arm 19 in a clockwise direction as viewed in Fig. 1 for the purpose of transferring a reserve bobbin from the magazine into the shuttle. When the lay reaches its extreme front center position the transerrer arm is in its lowest position and transfer of the bobbin is completed. As the lay moves rearwardly the transerrer arm rises in usual manner and returns to its normal raised position.

The lay 10 is provided in the present instance with a center filling stop motion designated generally at 20 and having a filling fork 21 the tines of which point rearward or to the right as viewed in Fig. 11. The center filling stop motion oper-

ates in usual manner and if weft is not under the fork the latter is unsupported as the lay moves forwardly and falls to a low position with resultant loom stoppage. The center fork operates each pick of the loom and in order to permit continued loom operation it must be supported by weft during a part of each forward motion of the lay.

Except for the pivotal mounting for the thread holder lever 6 the matter thus far described is of usual construction and operates in the usual manner. In the past the thread holder has not been mounted for back and forth motion in looms equipped with stationary reserve bobbin magazines. It is to be understood that the geared thread holder is shown herein for illustrative purposes and is only one of several types of thread holders which can be employed to hold the weft ends 3 leading from the reserve bobbins.

In carrying the present invention into effect a stud 25 is secured to a stand 26 fastened to the loom frame and has rockably mounted thereon an operator lever designated generally at 27. Lever 27 has a hub 28 pivoted on stud 25, an upstanding arm 29 connected preferably by a flexible cable 30 to the arm 6 at a point 31 thereof, and a substantially horizontal resilient arm 32. The forward or left end of arm 32 as viewed in Fig. 10 has mounted thereon a roll 35 having a peripheral groove 36 between flanges 37, see Fig. 3. Arm 32 is normally disposed as shown in full lines in Fig. 2, but because of its resilience is capable of movement to the dotted line position.

A support 40 secured at 41 to the stud 25 has a controller lever 42 pivoted thereon at 43. A tension spring 44 connected to a lug 45 on support 40 and to lever 42 tends normally to hold the latter in the full line position shown in Fig. 2. Extending upwardly from the lever 42 and rigid therewith is a positioning pin 46, see Figs. 2 and 4, which is closely adjacent to the resilient arm 32.

The free end of lever 42 is connected to a cable C which is trained around guide sheaves 47, 48, 49, 50 and 51 and is then connected at 52 to the transerrer arm 19. The sheaves 47 and 48 are rotatable on small stands 55 and 56, respectively, see Figs. 2 and 6, secured to the loom frame and turn in horizontal planes. Sheave 49 is rotatable on a stud 57 secured to a stand 58 fastened as at 59 to a part of the loom frame, see Fig. 6. The magazine M is provided with back and front arms 60 and 61, respectively, on which are rotatably mounted, respectively, the sheaves 50 and 51. The latter sheaves and also sheave 49 are rotatable preferably in vertical planes.

An actuator for operator lever 27 is shown here as a rotary cam 65 having a hub 66. This cam, see Fig. 12, has a low area 67 connected by an incline 68 to a high area 69 and the latter is connected by a decline 70 to the low area 67. The cam is keyed to the shaft 16 at 71 in such position that the incline 68 will preferably be close to but not quite in lateral register with the roll 35 when the transerrer arm begins its downward motion on a weft replenishing beat of the loom.

In operation, a weft replenishing operation will begin as the lay approaches its front center position on a beat of the loom when depleted shuttle S is at the magazine end of the loom. Under these conditions the transerrer arm 19 will be rocked as already described and in moving downwardly will exert a tension on the cable C the effect of which is to rock controller lever 42 from

the position shown in Fig. 8 to the full line position shown in Fig. 9, thereby causing the positioning pin 46 to move the resilient lever arm 32 to the dotted line position shown in Fig. 2 and to the full line position shown in Fig. 9 to move the roll 35 laterally into alignment with the periphery of the cam 65. This motion occurs while the low area of the cam is in lateral register with roll 35 just before the incline 68 reaches the roll, and a short time thereafter due to continued turning of the cam the incline 68 will enter the groove 36 when the lay is at or near its front center position. Thereafter the roll is held in alignment with the cam due to the flanges 37 as the transerrer arm returns to its normal raised position.

As the roll is lifted by the incline 68 lever 27 is rocked from the full line to the dotted line position, Fig. 10, and acts through its arm 29 and connector 30 to move the thread holder H rearwardly from the full line to the dotted line position shown in Fig. 10. The cam is so designed that it will cause the holder H to occupy the rear dotted line position shown in Fig. 10 at about the time the shuttle is picked, or when the lay is at or near its top center position represented in full lines, Fig. 11, to hold the weft end W of the transferred bobbin B in a position favorable for self-threading of the shuttle. The shuttle will then be picked to the opposite side of the loom and will pass the fork 21, and preferably at some time prior to completion of the shuttle flight the decline 70 will arrive under the roll 35 and the latter will be pulled down by a return tension spring 75 one end of which is connected at 76 to the arm 6 and the other end of which is connected to a stationary part 77 of the magazine, see Fig. 7. When the low area 67 of the cam arrives under the roll 35 the latter will be able due to the resilience of arm 32 to move laterally out of alignment with the cam back to its normal full line position shown for instance in Fig. 2. A stop pin 86, see Figs. 2 and 10, fixed on stand 26 engages a finger 81 of lever 27 to hold the roll 35 at a proper elevation above the low area 67 to enable the roll to clear the cam.

Movement of the roll 35 down the decline 70 will be accompanied by forward movement of the thread holder by return spring 75 so that the thread from the shuttle will occupy the position W shown in dotted lines in Fig. 11 and will pass under the fork 21. At this time the lay 10 may be in a rearward position as indicated in dotted lines, Fig. 11. It is desirable that the thread holder be in its forward position, dotted lines Fig. 11, when the lay is at or near its bottom center position while moving forwardly, although the invention will operate satisfactorily if the thread holder reaches its forward position slightly before or after the lay reaches its bottom center position.

As contemplated herein the cam may be considered as the actuator for the thread holder, the lever 27 and the connector 30 may be considered as the operator means connected to the movable thread holder, and the lever 42 and parts associated with it may be considered as control means connected to the bobbin transerrer mechanism which includes latch 18 and arm 19. More generally, all of these parts as well as the return spring 75 may be considered to be operating mechanism for the thread holder normally ineffective to move the thread holder but caused

to operate as described by the transerrer mechanism A.

The transerrer arm 19 will ordinarily start its bobbin transferring operation at a time when the lay is between its bottom and front center positions, and the roll 35 will clear itself from the cam when the low area 67 arrives under it while the lay is approximately on its next bottom center position, hence the whole operation occurs in less than one complete rotation of the shaft 16, and it is for this reason that a one-pick cam can be used when control is derived from the transerrer mechanism.

As the transerrer arm starts to rise after a bobbin changing operation as the lay moves rearwardly spring 44 will contract to keep cable C taut and engaged with its sheaves 47-51. At this time one of the flanges 37 of the roll will be engaged with the cam to hold the roll aligned with the latter despite movement of pin 46 away from arm 32 as spring 44 moves arm 42 from the full line to the dotted line position, Fig. 9.

From the foregoing it will be seen that the invention sets forth simple means whereby the bobbin transerrer mechanism of a loom is utilized to control operating mechanism which when in operation swings the thread holder H rearwardly to favor self-threading of the shuttle and then moves the thread holder forwardly to favor movement of the thread under the filling fork. The transerrer mechanism which transfers the bobbin and creates the need for moving its thread as described also causes mechanism normally inoperative to move the thread holder to move the thread. It will also be seen that initiation of the operation, being effected by the bobbin transerrer mechanism, permits the use of a cam which rotates once for each beat or pick of the loom, this being possible because of the fact that less than one pick elapses between engagement of the bunter 17 with the latch 18 and arrival of the lay at or about its next bottom center position when the roll 35 clears itself with respect to the cam. Also, the controller including lever 42 is mounted to move independently of the lever arm 32 and can be moved back to its normal position by spring 44 to keep the cable C taut and engaged with its sheaves 47-51 as the transfer arm rises.

Having now particularly described and ascertained the nature of the invention and in what manner the same is to be performed, what is claimed is:

1. In thread control means for a weft replenishing loom having a lay provided with a center filling stop motion fork and a self-threading shuttle for replenishment by a reserve bobbin from which a thread extends, a thread holder to which the thread is attached mounted to be located either in front or rear position in the loom, operating mechanism for the thread holder capable when operating to effect movement of the latter to the rear position thereof to facilitate self-threading of the shuttle when the latter is picked subsequent to replenishment by the bobbin and thereafter effecting movement of the thread holder to locate the latter in forward position to move the thread under the filling fork, said operating mechanism normally being inoperative and ineffective to cause said movements of the thread holder, and bobbin transerrer mechanism including a part moved by a force derived from the lay on a beat of the loom only when a bobbin is transferred effective on a weft replenishing beat of the loom to transfer said bobbin into said

shuttle and also cause operation of said operating mechanism to effect said movements of the thread holder.

2. In thread control means for a weft replenishing loom having a lay reciprocated by a shaft which rotates once each beat of the loom and provided with a center filling stop motion fork, the loom having a self-threading shuttle to be replenished by a reserve bobbin from which a thread extends, a thread holder to which the thread is attached mounted to be located either in front or rear position in the loom, operating mechanism for the thread holder including a rotary cam secured to said shaft normally inoperative to move said thread holder but effective when operating to move the thread holder to rear position to facilitate threading of the shuttle when the latter is picked subsequent to replenishment by said bobbin and thereafter effective to locate the thread holder in forward position to facilitate movement of the thread under said filling fork, and a bobbin transerrer arm normally at rest but having an operative movement derived from the lay on a weft replenishing beat of the loom only when a bobbin is transferred and effective when having said operative movement to transfer said bobbin into said shuttle and also cause operation of said operating mechanism by said cam.

3. In thread control means for a weft replenishing loom having a lay provided with a center filling stop motion fork and a shuttle for replenishment by a reserve bobbin from which a thread extends, a thread holder to which the thread is attached mounted to be located alternately in front and rear positions in the loom, a bobbin transerrer arm which is given a bobbin transferring movement by the lay on a replenishing beat of the loom only to insert the reserve bobbin into the shuttle, an actuator moving during loom operation, and operator means connected to the thread holder normally disengaged from the actuator but movable into position for engagement by the actuator and when engaged by the latter being caused thereby to effect location of the thread holder and said thread in rear position to facilitate threading of the shuttle when the latter is picked subsequent to insertion of the reserve bobbin into the shuttle and thereafter effect location of the thread holder in the front position thereof to move the thread forwardly under the center filling fork, said bobbin transerrer arm when having said movement derived from the lay to effect insertion of the reserve bobbin into the shuttle also effecting movement of the operator means into position for engagement by the actuator.

4. The thread control means set forth in claim 3 wherein said operator means includes a lever having an arm movable into and out of alignment with the actuator.

5. In thread control means for a weft replenishing loom having a lay provided with a center filling stop motion fork and a shuttle for replenishment by a reserve bobbin from which a thread extends, a thread holder to which the thread is attached mounted to be located either in front or rear positions in the loom, means causing the thread holder to have a tendency to be in front position, an actuator moving during loom operation, bobbin transerrer mechanism having a part which is given a bobbin transferring movement by the lay on a replenishing beat only of the loom to insert the reserve bobbin into the shuttle to effect replenishment of the latter, operator means connected to the thread holder normally dis-

engaged from the actuator but movable into position for engagement by the actuator and when engaged by the actuator being caused by the latter to locate the thread holder in rear position to facilitate threading of the shuttle when the latter is picked subsequent to replenishment thereof and thereafter enabling the thread holder due to said tendency thereof to return to the front position thereof to move the thread forwardly under the center filling fork, said part of the bobbin transerrer mechanism when having said bobbin transferring movement being effective to move the operator into position for engagement with the actuator.

6. In thread control means for a weft replenishing loom having a lay provided with a center filling stop motion and a shuttle for replenishment by a reserve bobbin from which a thread extends, a thread holder for the thread mounted to be located either in front or rear position in the loom, an actuator moving during loom operation, bobbin transerrer mechanism having a part which is given a movement by the lay on a replenishing beat of the loom only to insert the reserve bobbin into the shuttle, operator means connected to the thread holder normally disengaged from the actuator but movable into position for engagement by the actuator and when engaged by the actuator being caused by the latter to locate the thread holder in rear position to facilitate threading of the shuttle when the latter is picked subsequent to insertion of the reserve bobbin thereinto by the transerrer mechanism, and return means effective thereafter to locate the thread holder in front position to move the thread under the center filling fork, said part of the transerrer mechanism being effective when inserting the reserve bobbin into the shuttle to effect movement of said operator means into position for engagement by the actuator.

7. In thread control means for a loom having a lay provided with a center filling stop motion and a shuttle for replenishment by a reserve bobbin from which a thread extends, a thread holder for the thread mounted to be located either in front or rear position in the loom and having a tendency to occupy the front position thereof, an actuator cam having high and low areas rotating during loom operation, operator means connected to the thread holder normally out of alignment with the actuator cam but movable over the low area of the cam into alignment with the latter at a given time in the forward motion of the lay for engagement by the cam and when engaged by the cam being given a movement by said high area to locate the thread holder in rear position to facilitate threading of the shuttle when the latter is picked subsequent to replenishment by the reserve bobbin, said operator means thereafter due to said tendency and in cooperation with said actuator cam effecting movement of the thread holder to the front position thereof to move the thread forwardly under the center filling fork, and bobbin transerrer mechanism effective to transfer the reserve bobbin into the shuttle and also effective at said given time to move said operator means over said low area into alignment with the cam.

8. The thread control means set forth in claim 7 wherein said operator means includes a lever having a resilient arm normally out of alignment with the actuator but capable of being bent by a force derived from the transerrer mechanism to move into alignment with the actuator cam, the arm due to the resilience thereof returning to normal position when said low area due to turn-

ing of the cam comes under the operator means.

9. In a loom having a center filling fork on a lay provided with a shuttle to be replenished by a reverse bobbin from which a thread extends and having a shaft which moves the lay rearwardly from front center position through top center position to back center position and then moves the lay forwardly through bottom center position to front center position to complete a one-pick cycle of the loom, bobbin trans-ferrer mechanism which on a weft replenishing beat of the loom has an operative movement at a given time in said one-pick cycle of the loom to insert the bobbin into a shuttle as the lay moves forwardly from back center position to front center position, a thread holder for the thread mounted to move backwardly from the normal forward position thereof and tending to return forwardly to the normal position thereof, an actuator cam secured to and rotating with the shaft, operating means connected to the thread holder normally out of alignment with the cam but movable into alignment therewith for engagement thereby and when engaged by the cam being caused by the latter to move the thread holder rearwardly as the lay moves rearwardly from the front center position thereof to position the thread favorably for self-threading of the shuttle when the latter is picked during rearward motion of the lay subsequent to replenishment thereof by the bobbin and said operator means thereafter cooperating with the actuator cam to effect forward motion of the thread holder to the normal position thereof before a time in the next one-pick cycle corresponding to said given time to facilitate movement of the thread under the filling fork, and means operated by the trans-ferrer mechanism when the latter has said operative movement to move the operator means into alignment with the actuator cam during said given time.

10. In thread control means for a loom having a back and forth reciprocating lay provided with a center filling stop motion fork and a reserve bobbin from which a thread extends and wherein a shuttle is picked during rearward motion of the lay, a thread holder connected to the thread, the thread holder having a tendency to be in forward position but mounted to be mov-

able to a rear position, an actuator moving regularly in one-pick cycles during operation of the loom, an operator connected to the thread holder normally out of operative position relative to the actuator, bobbin trans-ferrer mechanism having a bobbin transferring movement from the normal position thereof on a weft replenishing beat of the loom to insert the bobbin into the shuttle to replenish the latter during a time 5 in one one-pick cycle of the actuator beginning as the lay approaches its front position and ending when the lay reaches its front position, the trans-ferrer mechanism returning to the normal position thereof during said rearward motion of the lay, and a controller connecting the operator and bobbin trans-ferrer mechanism effective when the latter has said transferring movement to move the operator into operative position relative to the actuator, the actuator thereupon engaging the operator prior to return of the trans-ferrer mechanism to the normal position thereof and effecting location of the thread holder in rearward position to facilitate threading of the shuttle when the latter is 10 picked and the operator and actuator thereafter enabling the thread holder due to said tendency thereof to effect location of the thread holder forwardly prior to a time in the next one-pick cycle of the actuator corresponding to said given time 15 in said one one-pick cycle to move the thread of the replenished shuttle forwardly under the filling stop motion fork.

11. The thread control means set forth in claim 10 wherein said actuator includes a rotating cam and said operator includes a grooved roll which remains engaged with the cam subsequent to return of the trans-ferrer mechanism to the normal position thereof.
